UNITED STATES PATENT OFFICE

JOHN J. LEE, OF BROOKLYN, NEW YORK, ASSIGNOR TO ALBERT BEHREND AND JOSEPH ROTHSCHILD, DOING BUSINESS AS COPARTNERS UNDER THE FIRM-NAME OF BEHREND & ROTHSCHILD, OF NEW YORK, N. Y.

HOLLOW BODY AND METHOD OF MAKING SAME.

1,274,174.

Specification of Letters Patent. Patented July 30, 1918.

Application filed October 16, 1917. Serial No. 196,787.

To all whom it may concern:

Be it known that I, JOHN J. LEE, a citizen of the United States, and a resident of Brooklyn, in the county of Kings and State 5 of New York, have invented certain new and useful Improvements in Hollow Bodies and Methods of Making Same, of which the following is a specification, reference being made to the accompanying drawings, forming part thereof.

My invention relates to the formation of hollow bodies more particularly for toys and decorations of nearly spherical shape, which bodies are extremely light in weight while 15 possessing exceptional strength and durability and a hard, glistening finish without undesirable brittleness. Such improved hollow bodies are usually highly colored and are commonly used for decorating Christmas trees, and the aim of my invention is to produce such hollow bodies by a simple and inexpensive process using a rubber balloon body as a base and thereby producing such bodies having, among other things, the advantages which I have hereinbefore set forth.

I attain this result by the method which is partially illustrated in the accompanying drawings in which—

30 Figure 1 is a vertical sectional view of the balloon body mounted on a tapered stick before dipping;

Fig. 2 is a vertical sectional view similar to that shown in Fig. 1 with the different 35 coatings shown in a somewhat exaggerated form;

Fig. 3 is an enlarged detail section of a part of the hollow body shown in Fig. 2; and

40 Fig. 4 is a front view of the completed hollow body with the neck shown in sectional elevation.

Similar numerals refer to similar parts throughout the several figures.

45 In carrying out my improved method, I take as a base for the complete hollow body a balloon body 5 made of thin rubber of pure quality and extreme elasticity, which will allow same to be inflated and expanded 50 to many times its normal size. I then in-

sert in the balloon neck 6 the stick or rod 7, preferably tapered toward its point 8 which shall contact with the top 9 of the balloon body 5, as shown in Fig. 1. The balloon body 5 is now inflated and expanded to the 55 desired size in any convenient manner, the stick 7 serving not only to close the opening within the neck 6 after inflation, but also to preserve the spherical form and normal contour of the balloon body 5 in the dipping 60 process that follows.

I then prepare the solution for the first coating of the balloon body which coating is superimposed upon the outer surface of the balloon body 5. I form this solution by 65 mixing together four parts by weight of glue, one part by weight of wood alcohol preferably of ninety-five (95%) per cent. strength, one part by weight of white lead, and one part by weight of powdered chalk. 70 I first mix the glue with sufficient water to dissolve same with the aid of heat, and then add the wood alcohol to the dissolved glue which causes the glue to form a viscous mass. The white lead and powdered chalk are 75 mixed together, and thereafter added to the melted glue, the viscosity of the mass preventing the mixed white lead and chalk from sinking to the bottom of the glue. I have found that the white lead imparts durability and strength to the coating thereafter to be formed by rendering the completed 80 hollow bodies less likely to become shattered or broken, and the white lead also prevents deterioration of the glue, while the addition of powdered chalk to the mixture assists in the subsequent drying of the coating by acting as an absorbent filler. This composition is thoroughly mixed in the presence of heat until it forms a solution of suitable uniformity and consistency for dipping therein of the balloon body 5, which dipping produces a sticky coating 10 on the balloon body 5. This coating 10 is permitted to partially 85 dry, but before the coating 10 has completely dried to form the shell for the hollow body, it is thoroughly sprinkled and covered with powdered aluminum bronze forming a coating 11 which adheres to the coating 10. The hollow body with the coatings 10 and 11 is 90 95 100

now thoroughly dried. This aluminum bronze coating 11 affords a hard surface for the hollow body now formed and it also imparts to the hollow body an inner reflecting surface for the outer varnish coating 12. This outer coating 12 is a solution made of varnish into which the coloring substance is stirred to give the desired color to the completed body; for example, I have used the 10 varnish solution known as "bronzing liquid" in which red oil colors are soluble. The balloon body is dipped into this colored varnish solution and then allowed to dry whereby the varnish coating 12 having a hard glistening surface of high color is formed, the 15 colors being intensified by the aluminum bronze coating beneath. I then withdraw the tapered stick 7 from the neck 6 of the hollow body, and thereafter close the neck 6 by the 20 plug 13 which may have the staple 14 mounted therein, as shown in Fig. 4, from which the hollow body may be conveniently suspended.

It is obvious that the several coatings 25 adhering to the outer surface of the hollow body 5 not only hold same in its expanded position and shape and of any desired size, but also tend to form a homogeneous outer shell for the entire body, each coating closely 30 adhering to its adjacent coating and the coating 10 firmly holding the balloon body 5 in position.

I claim as my invention:

1. The method of making a hollow homogeneous body which consists in inserting 35 within an elastic rubber body an elongated tool, then inflating the rubber body to the desired size, whereby the tool serves to maintain the rubber body inflated and in its expanded contour, thereafter dipping the inflated body and tool in a thereto adhering coating solution and drying same to form an indivisible shell body self-maintainable at its predetermined inflated size, and finally 45 withdrawing the tool from the hollow body so formed.

2. The method of making a hollow homogeneous body which consists in inserting within an elastic rubber body and along its 50 longitudinal axis an elongated tool, then inflating the rubber body to the desired size, whereby the tool serves to maintain the rubber body inflated and in its longitudinally expanded contour, thereafter dipping the inflated body and tool in a thereto adhering coating solution and drying same to form an indivisible shell body self-maintainable at its predetermined inflated size, and finally 55 withdrawing the tool from the hollow body so formed.

3. The method of making a hollow homogeneous spheroidal body which consists in inserting within an elastic rubber body an elongated tapered tool, then inflating the 65 rubber body to the desired size, whereby the

tool serves to maintain the rubber body inflated and in its expanded contour, thereafter dipping the inflated body and tool in a thereto adhering coating solution and drying same to form an indivisible shell body 70 self-maintainable at its predetermined inflated size, and finally withdrawing the tool from the hollow body so formed.

4. The method of making a hollow homogeneous spheroidal body which consists in 75 inserting within an elastic rubber body and along its longitudinal axis an elongated tapered tool, then inflating the rubber body to the desired size, whereby the tool serves to maintain the rubber body inflated and 80 in its longitudinally expanded contour, thereafter dipping the inflated body and tool in a thereto adhering coating solution and drying same to form an indivisible shell body self-maintainable at its predetermined 85 inflated size, and finally withdrawing the tool from the hollow body so formed.

5. As a new article of manufacture, a hollow homogeneous body comprising an inner expanded elastic rubber body, a thereto adhering coating shell indivisibly compounded with said body made by mixing glue, wood alcohol, white lead and chalk in substantially the proportions described, self-maintainable at any predetermined size. 95

6. As a new article of manufacture, a hollow homogeneous body comprising an inner expanded elastic rubber body, a thereto adhering coating shell indivisibly compounded with said body made by mixing glue, wood alcohol, white lead and chalk in substantially the proportions described, self-maintainable at any predetermined size, and a superimposed outer varnish coating. 100

7. As a new article of manufacture, a hollow spheroidal body comprising an inner expanded elastic rubber body, a thereto adhering coating shell homogeneously compounded with said body made by mixing glue, wood alcohol, white lead and chalk in 105 substantially the proportions described, whereby the body is thereby maintained in its expanded form, and a superimposed outer varnish coating combined with coloring substances. 110

8. As a new article of manufacture, a hollow spheroidal body comprising an inner expanded elastic rubber body, a thereto adhering coating shell homogeneously compounded with said body made by mixing glue, wood alcohol, white lead and chalk in substantially the proportions described, whereby the body is thereby maintained in its expanded form, an aluminum bronze coating embodied in the outer surface of 120 said coating, and a superimposed outer varnish coating combined with coloring substances. 125

9. As a new article of manufacture, a homogeneous hollow body comprising an 130

inner expanded elastic rubber body, a thereto adhering coating homogeneously compounded with said body made by mixing glue, wood alcohol, white lead and chalk in substantially the proportions and manner described, whereby an indivisible shell body is formed self-maintainable in its expanded

size, an aluminum bronze reflecting coating embodied in the outer surface of said coating, and a superimposed translucent outer 10 varnish coating combined with coloring substances.

JOHN J. LEE.
